UNITED STATES PATENT OFFICE

CHARLES H. BROWN AND CHARLES B. BROWN, OF FLUSHING, NEW YORK

SHOE CONSTRUCTION

Application filed January 15, 1931. Serial No. 508,906.

Among the principal objects which the present invention has in view are: To provide rigid supports for the outer edges of shoes, and more particularly for the outer edges of the shank-arch of shoes, said supports being constructed to underlie the inseams of said shoes by a series of laterally extended members spread apart to be embedded in the said inseams; to provide shank irons for said shoes adapted for lateral adjustment to fit varied widths between said inseams; to provide means for avoiding the usual abrasion of the ends of shank irons upon the sole members of shoes; to provide a rigid sole-shaping member, and to provide said shank and said sole-shaping members in cooperative relation to augment the strength and improve the shape of the shank-arch of the shoe.

Drawings

Figure 1 is a view of the under side of a shoe constructed and arranged in accordance with the present invention.

Figure 2 is a similar view, the wear-sole and heel being removed to expose the inner structure of the bottom of a shoe constructed and arranged in accordance with the present invention.

Figure 3 is a longitudinal section, the section being taken as on line 3-3 as in Figure 2.

Figure 4 is a detailed view of the shank iron employed in the construction of the shoe, the parts whereof having been spread laterally to accommodate a wide shoe construction.

Figure 5 is a similar view, the parts of the shank iron having been laterally constricted to accommodate a narrow shoe construction.

Figure 6 is a sectional view of the shank portion of a shoe having a shank iron constructed as herein set forth, the section being taken as on line 6-6 as in Figure 4.

Figure 7 is a detailed view showing the

forward end of the shank iron in combination with a fillet arranged to provide for the metatarsal arch of the human foot.

Description

Shank irons providing means for supporting a shoe structure at the outer edges of the shank-arch have been employed. Flanges rigidly upset, as a continuous feature of construction, have extended over the inseams of shoes to afford a rigid support therefor. The bulkiness of such constructions has proved objectionable for the reasons that special shank irons have been required for every variation and change in the width of shoes. Thus narrow shank irons, medium shank irons and wide shank irons have had to be provided.

In the present invention the above mentioned objections have been overcome by constructing shank irons, as seen in the drawings, in two sections or halves, which overlap and which are adjustable relatively to a variety of total widths.

The first-mentioned objection has been overcome by providing a shank iron having movable over-lapping sections 11 and 12. The sections 11 and 12 are slidably connected, the section 11 being provided with curved slots 13, while the section 12 is provided with headed studs 14, the shanks of which extend through the slots 13.

By observation of Figures 4 and 5, it will be seen that the sections 11 and 12 may be laterally adjusted and so accommodate the space provided between the inseams of a shoe at the shank-arch thereof.

To support the said inseams, the said sections are each provided with a series of upstanding and laterally extending lugs 15.

As shown in Figures 2 and 3 of the drawings, the lugs 15 extend under the inseams 16. It will also be observed that the lugs 15 are relatively narrow and spaced apart. This construction provides bodies of the sections

11 and 12 which are ridged at the outer edges adjacent said lugs. These ridges 23 fill in the spaces next to the edge of the inseams, which spaces are usually neglected or left unfilled by the cork filler when same is being placed over the shank iron in shoe construction. The ridges also serve to augment the rigidity of the shank iron sections.

As seen in the drawings, the sections are provided at the advanced end of the shank iron with forward-reaching lugs 17. These in service reach forward, as is seen best in Figure 2 of the drawings, and support the inseams 16 up to and adjacent the bending line or moment of the shoe.

As shown best in Figure 3 of the drawings, the shank iron rests upon the fillet 18. This fillet 18 may be constructed of any material, preferably wood. A shoulder 19 is provided therein to form an abutment for the forward end of the shank iron.

As will be seen best in Figure 2, the fillet 18 is formed to shape the rear edge 22 of the molded portion of the sole 20, where the same is extended rearwardly in accordance with the style of the shoe adopted.

It is obvious that when thus arranged, the abrasion on the sole members formerly objected to is avoided—all abrasion being now received by the fillet 18. The fillet 18 is held firmly in position by the sole 20, the shank iron and the filler 21 with which the shoe is provided.

The result of such construction is that during the life of the shoe, the rear shape of the wear-sole is maintained. As a result of the employment of the shoulder 19 against which the shank iron rests, the shank iron is prevented from shifting in the shoe construction.

In Figure 7 of the drawings, a modified form of the fillet 18 is shown as indicated by the numeral 24. The modification consists in building up the forward end 25 of said fillet to support, in elevated position, the forward end of the shank member, and to provide a depression between the shank portion and the ball portion of the shoe, caused by the shoulder 26. This depression forms a natural rest or drop into which the metatarsal structure, or bones forming same, drop.

From the foregoing it will be seen that the objections cited have been avoided by the present construction.

Claims:

1. A shoe construction having an insole and upper secured thereto by inseams extending under the shank-arch of the shoe in spaced relation, a shank iron comprising a plurality of pivotally connected members adapted to rest upon said insole between said inseams and to be expanded laterally to rest against the edges of said inseams, and means integral with said members for extending over said inseams to support the same in service.

2. A shoe construction having an insole and

upper secured thereto by inseams extending under the shank-arch of the shoe in spaced relation, a shank iron comprising a plurality of pivotally connected members adapted to rest upon said insole between said inseams and to be expanded laterally to rest against the edges of said inseams, and means integral with said members for extending over said inseams to support the same in service, said means embodying a plurality of laterally upset and extending lug members adapted to extend over said inseams, said members being spaced apart.

3. A shoe construction having an insole and upper secured thereto by inseams extending under the shank-arch of the shoe in spaced relation, a shank iron comprising a plurality of pivotally connected members adapted to rest upon said insole between said inseams and to be expanded laterally to rest against the edges of said inseams, and means integral with said members for extending over said inseams to support the same in service, said means embodying a plurality of laterally upset and extending lug members adapted to extend over said inseams, said members being spaced apart, the said lugs at the forward end of said shank iron members being inclined to underlie the said inseams at the forward ends thereof.

4. A shoe construction having an insole and upper secured thereto by inseams extending under the shank-arch of the shoe in spaced relation, a shank iron adapted to rest on the said insole between said inseams, said shank iron being adapted for lateral adjustment to accommodate differences in spacings between said inseams, and a rigid fillet adapted to receive the forward end of said shank iron members to protect the wear-sole of the shoe from abrasion thereon.

5. In a shoe construction as characterized, a shank iron comprising a plurality of metal plates slidably connected for lateral extension and adjustment, the said plates having a plurality of laterally extended lugs for extending over an adjacent inseam in service, said lugs being spaced apart to permit said plates to accommodate the curvature of the shank portion of a shoe so constructed.

6. In a shoe construction as characterized, a shank iron comprising a plurality of metal plates slidably connected for lateral extension and adjustment, the said plates having a plurality of laterally extended lugs for extending over an adjacent inseam in service, said lugs being spaced apart to permit said plates to accommodate the curvature of the shank portion of a shoe so constructed, two or more of said lugs at the forward end of said plates being disposed in angular relation to the axis of said shank iron to reach forward thereof to cover said inseams adjacent the ends thereof.
